(57) **CLAIM**

The ornamental design for a case for a recording medium, as shown.

DESCRIPTION

FIG. 1 is a front, bottom, right perspective view of a case for a recording medium showing our new design;
FIG. 2 is a rear, bottom, left perspective view thereof;
FIG. 3 is a front elevational view thereof;
FIG. 4 is a rear elevational view thereof;
FIG. 5 is a left side elevational view thereof;
FIG. 6 is a right side elevational view thereof;
FIG. 7 is a top plan view thereof; and
FIG. 8 is a bottom plan view thereof.
FIG. 9 is a front elevational view thereof in a closed state;
FIG. 10 is a rear elevational view thereof;
FIG. 11 is a left side elevational view thereof;
FIG. 12 is a right side elevational view thereof; and
FIG. 13 is a top plan view thereof, a bottom plan view thereof being a mirror image.

1 Claim, 8 Drawing Sheets
